ELEVATOR CONTROL SYSTEM

Danilo Santini, Chicago, Ill., assignor to Westinghouse Electric Elevator Company, Chicago, Ill., a corporation of Illinois

Application October 29, 1932, Serial No. 640,180

1. Claim. (Cl. 172—239)

My invention relates to elevator control systems and has particular relation to elevator control systems embodying means for overcoming the effects of residual magnetism in dynamo-electric devices employed therein.

My invention will be described as applied to an elevator control system of the well known Ward-Leonard or variable-voltage type but it should be understood that it is not necessarily limited to this particular type of control system.

I have found that in a multi-speed motor control system of the variable-voltage type, in which an elevator car is accelerated to a high speed for long runs and an intermediate or lower speed for shorter runs, that if the initial run of an elevator car immediately after a reversal in its direction of movement is a short run in which it attains only an intermediate speed, the speed of the elevator car is less than is desirable.

10 I have concluded that the diminished speed of the car immediately after reversal is due to the opposing effect of the residual magnetism in the field cores and other magnetic structure of the generator of the variable-voltage system. That 15 is, although the separately excited shunt field winding of the main generator which supplies power to the elevator motor is energized to the same degree before and after reversal, the speed of the elevator car is less after reversal than before, due to the opposing magneto-motive force 20 exerted by the residual magnetism against the magneto-motive force set up by the current flowing through the shunt field winding. The voltage generated by the main generator and supplied to the elevator motor is thus diminished 25 from a predetermined voltage which is necessary to actuate the motor to drive the elevator car in accordance with a predetermined speed characteristic.

30 The ultimate result of the effect of the residual magnetism is that the length of time between the starting and stopping of an elevator car for a short run immediately after reversal is increased an appreciable amount over the length of time 35 which should be consumed in order that the car follow a predetermined speed characteristic.

In order to overcome this disadvantageous effect I propose to over-excite the generator shunt field winding a predetermined amount necessary 40 to compensate for, or overcome, the effect of the opposing magneto-motive force exerted by the residual magnetism, in the event that the initial run after reversal is a short run in which the elevator car does not attain maximum speed.

45 50 55

Any suitable means for over-exciting the sepa-

rately excited shunt field winding of the generator may be employed, such as short-circuiting a portion of the resistance connected in series-circuit relation or potentiometer relation with the shunt field winding or employing a voltage compounding means, such as a regulating generator, the voltage from which is suitably controlled to increase the degree of compounding normally employed to energize the shunt field winding.

5 It is an object of my invention, therefore, to 10 compensate for the effect of residual magnetism in the field cores of dynamo-electric devices employed in elevator control systems.

It is a more specific object of my invention to 15 vary the degree of excitation of the shunt field winding of a generator of a variable-voltage type of control in order to compensate for the effect of residual magnetism in diminishing speed, in the event of the operation of the elevator car at an intermediate speed immediately subsequent to 20 a reversal in the direction of movement of the elevator car.

Other objects of my invention will be apparent 25 from the following description and explanation of the operation of my invention when read in connection with the accompanying drawings, wherein

Figure 1 is a diagram illustrating one embodiment 30 of a control system to which my invention is adapted, and

Fig. 2 is a view showing an elevator car having inductor relays thereon and a complete set of stationary inductor plates for one floor.

Referring to Fig. 1, a suitable driving motor DM, illustrated as of a three-phase induction type and connected to alternating current supply conductors m, n and o through a suitable switch 11, is employed to drive the armature of a direct-current generator G, the armature winding GA of which is connected in closed-loop circuit relation with the armature winding MA of a motor M for driving the elevator car C.

35 The generator G is provided with a separately excited shunt field winding GF and a series field winding GSF which is connected in series-circuit relation with the armature winding GA. The motor M is provided with a separately excited shunt field winding MF which is suitably controlled.

40 45 The elevator car C and its counterweight Cw are suitably supported by a cable Ca which extends around a drum D rotated by the motor M.

The motor M is provided with a suitable electro-magnetic brake B, comprising a brake drum BD which is secured to the shaft of the armature

55

of the motor, and a brake shoe B_5 which is biased into frictional relationship with the drum BD in a suitable manner and released from engagement therewith by a release coil or solenoid Rs which is energized whenever the elevator motor is actuated to start the car.

Direction relays 1 and 2, corresponding to the upward and downward travel of the elevator car, respectively, and energized by the operation of a car switch CS on the elevator car, are employed to reversibly control the connection of the generator shunt field winding GF to a pair of conductors L_1 and L_2 which supply suitable direct-current potential.

Acceleration and deceleration of the elevator car is effected by means of suitable resistors R_1 and R_2 connected in series-circuit relation with the generator shunt field winding GF , the resistors being controlled respectively by means of relays GR_4 and GR_6 .

A high speed inductor relay $3R$, an intermediate speed inductor relay $2R$ and a stopping inductor relay $1R$ are suitably disposed on the elevator car C , as shown in Fig. 2, for cooperating in succession with a suitably disposed group of inductor plates at each floor which comprise the up-direction high-speed inductor plate $3U$, the up-direction intermediate-speed plate $2U$, the up-direction stopping plate $1U$, the down-direction high-speed plate $3D$, the down-direction intermediate-speed plate $2D$ and the down-direction stopping plate $1D$.

Inductor relay $3R$ is provided with a suitable energizing coil $3L$ and with suitable up-direction contact members $3UL$ and down-direction contact members $3DL$, the contact members being selectively actuated to open when the relay, with its coil energized, comes into adjacent relation with the high-speed plates $3U$ and $3D$, respectively. The contact members $3UL$ and $3DL$ of relay $3D$ control the relay GR_6 and, when opened, effect the deenergization thereof to cause the resistor R_2 to be reinserted in series-circuit relation with the generator shunt field winding GF to effect the initial step of deceleration of the elevator car.

Relay $2R$ is similarly provided with an energizing coil $2L$ and with up-direction contact members $2UL$ and down-direction contact members $2DL$, the contact members being selectively actuated to open whenever the relay with its coil energized, comes into adjacent relation with the intermediate speed inductor plates $2U$ or $2D$ respectively. The contact members $2UL$ and $2DL$ of relay $2R$, control the relay GR_4 and, when opened, effect the deenergization thereof to cause the reinsertion of resistor R_1 in series-circuit relation with the generator shunt field winding GF to thereby effect the deceleration of the elevator car to low speed.

Inductor relay $1R$ is provided with an energizing coil $1L$ and with up-direction contact members $1UL$ and down-direction contact members $1DL$, the contact members being selectively actuated to open when the relay, with its coil energized, comes into adjacent relation with the stopping inductor plates $1U$ or $1D$ respectively. The contact members $1UL$ and $1DL$ of relay $1R$ are connected respectively in series-circuit relation with the energizing coils of direction relays 1 and 2 and, when opened, effect the deenergization of the corresponding relay to interrupt the circuit for energizing the generator shunt field winding GF which results in the complete stopping of the elevator car.

A regulating generator RG is provided which has an armature winding RA and a field winding RSF which is connected in the loop circuit, including the armature windings GA and MA of the generator G and the motor M respectively. The armature winding of the regulating generator RG is connected in series circuit relation with the generator shunt field winding GF and is driven at a constant speed by a suitable motor, not shown, to generate a voltage in proportion to the amount of current flowing in the loop circuit connecting the armature windings of the generator G and the motor M .

A suitable potentiometer resistor PR , which is connected across the brush terminals of the regulating generator RG is provided for varying the voltage in the energizing circuit of the generator field winding GF as desired.

A suitable resistor R is connected in shunt relation to the generator field winding GF and the potentiometer resistor PR for the purpose of completing a local energizing circuit for the field winding GF from the potentiometer as a source of energy.

A voltage responsive relay 31 , of well known construction, is connected across the brush terminals of the motor M in series-circuit relation with a suitable resistor r and is designed to be actuated only after the motor attains a predetermined speed such as the intermediate speed. Relay 31 controls the energization of the high-speed relay GR_6 and unless relay 31 is actuated, relay GR_6 cannot be energized to cause the elevator car to accelerate to high-speed.

An additional resistor R_3 is connected in series-circuit relation with the shunt field winding GF and a relay 3 is provided which is adapted to control this resistor to cause it to be short-circuited out of the energizing circuit of the generator field winding GF , in the event that the initial run of the elevator car immediately after a reversal in its direction of movement is such as not to enable the car to attain high-speed.

A pair of relays $80\ U$ and $80\ D$, which are controlled by the direction relays 1 and 2, are employed to control the energization of the relay 3 which is adapted to be initially energized upon the energization of high-speed relay GR_6 .

The relay 3 also controls the tap connection to the potentiometer resistor PR and causes a greater portion thereof to be included in series-circuit relation with the generator field winding GF in the event that the initial run of the elevator car immediately after reversal in its direction of travel is such that it does not attain high speed.

Although I have shown relay 3 as controlling both the resistor R_3 and the potentiometer resistor PR for the purpose of over-exciting the generator field winding to a predetermined amount necessary to overcome the opposing effect of the residual magnetism in the field cores of the generator G , it should be understood that either one may be suitably adapted to separately effect the same result as when both are employed together.

Furthermore, while I have shown a regulating generator RG as provided with only a single field RSF , it should be understood that it may also be provided with a differential field winding in the manner disclosed in the copending application of Kenneth M. White and George K. Hearn, Serial No. 489,766, filed October 20, 1930, issued October 25, 1932, as Patent No. 1,884,446, and assigned to the Westinghouse Electric Elevator Company.

My invention may best be understood by describing the various steps involved in a typical

operating cycle. Let it be assumed that the elevator car C is at the lower terminal or first floor and the operator desires to move the car to an upper terminal floor which may be, for example, the tenth floor of a building. After closing the car gate and the hatchway door at the lower terminal floor, the operator may move the handle of the car switch CS in a clockwise direction to an extreme position removed a suitable angular distance from the central position.

The car switch handle, preferably of insulating material is secured to a conducting sector 12 which is suitably pivoted at 13, and thus during the movement of the car-switch handle the sector 12 is moved thereby to engage a stationary contact finger 15 and complete a circuit for energizing the coil of up-direction relay 1, which circuit extends from supply conductor L1 through conductor 21 to sector 12, thence through contact finger 15, conductor 22, coil of relay 1, conductor 23, contact members 1UL of relay 1R, conductor 24, car gate-switch g, hatchway door-interlock switches d, in series, and safety switches ss, in series, to supply conductor L2.

The energization of relay 1 effects the closing of the normally open contact members a, b and c and the opening of the normally closed contact members d thereof. The opening of contact members d of relay 1 interrupts a circuit for energizing the coil of relay 80 U which, as will be subsequently explained, is energized at this time, the circuit for energizing relay 80 U extending from supply conductor L1 through conductor 25, contact members d of relay 1, conductor 26, coil of relay 80 U, conductor 27, normally closed contact members a of relay 80 D and conductor 29 to supply conductor L2. The reclosing of normally closed contact members a of relay 80 U, as a result of the deenergization thereof, completes a circuit for energizing the coil of relay 80 D, which circuit extends from supply conductor L1 through conductor 29, normally closed contact members d of relay 2, conductor 30, contact members a of relay 80 U, conductor 30a, coil of relay 80 D and conductors 32 and 28 to supply conductor L2. The effect of the deenergization of relay 80 U and the energization of relay 80 D will be explained hereinafter.

The closing of contact members a of relay 1 completes a circuit for energizing the release coil Rs of the brake B on the motor M, which circuit extends from supply conductor L1 through conductor 33, contact members a of relay 1, conductors 34 and 35, brake coil Rs and conductor 36 to supply conductor L2.

The closing of contact members b and c of relay 1 completes a circuit for energizing the separately excited shunt field winding GF of the main generator G and the generator, therefore, supplies an initial voltage to the armature winding MA of the motor M sufficient to start elevator car at low speed immediately upon the release of brake B. The circuit for energizing field winding GF, in this case, extends from supply conductor L1 through conductor 37, contact members b of relay 1, conductor 38, field winding GF, conductor 39, normally closed contact members b of relay 3, armature winding of generator RG, conductor 40, contact members c of relay 1, conductor 41, to the point 42, thence through conductor 43, normally closed contact members a of relay 3 and conductors 44 and 45 to the point 46 whence it extends through resistors R2 and R1 to supply conductor L2.

A local circuit, including the generator shunt field winding GF is also completed, which extends

from one brush terminal of the armature of the regulating generator RG through conductor 40, resistor R, conductors 31 and 33, field winding GF, conductor 39 and contact members b of relay 3, back to the brush terminal of opposite polarity 5 on the armature winding of generator RG. A current flows in this local circuit which is proportional to the current flowing in the loop-circuit connecting the armature windings GA and MA of the generator G and motor M respectively, and 10 depending upon the direction of flow of current in the loop circuit, increases or decreases the excitation of the generator field winding with respect to that which would occur due only to the other excitation. 15

As a result of the energization of the field winding GF, the generator G generates an initial voltage for supplying power to the motor M and causing it to drive the elevator car at low speed.

Although the sector 12 of the car switch CS 20 only momentarily engaged the contact finger 15 and although it is no longer in engagement therewith, the circuit for energizing the coil of relay 1 is maintained through a self-holding circuit established by the closing of normally open 25 contact members e of relay 1 which are connected in parallel-circuit relation with sector 12 and contact finger 15 of the car switch CS from supply conductor L1 to the coil of relay 1.

The car switch CS is so designed that, when its 30 handle is moved into the position of its clockwise extremity of movement, the sector 12 remains in contacting engagement with contact fingers 16 and 17. The engagement of sector 12 with contact finger 16 completes a circuit for energizing 35 the coil of relay GR4, which extends from supply conductor L1 through conductor 21 to the sector 12 of the car-switch, thence through contact finger 16, conductor 47, normally open contact members g of relay 1, conductor 48, contact members 2UL of inductor relay 2R, conductors 49 and 50, coil of relay GR4 and conductor 51 to supply conductor L2. Normally open contact members c of relay GR4, when closed by the energization 45 of the relay, complete a self-holding circuit for maintaining the energization of the relay independently of the position of the car-switch CS. Contact members c of relay GR4 are connected in parallel-circuit relation with sector 12 and contact finger 16 between supply conductor L1 and 50 the contact members g of relay 1.

The closing of normally open contact members a of relay GR4 completes a short-circuiting connection around resistor R1 and thus, in effect, removes the resistor R1 from the circuit for energizing the generator shunt field winding GF. As a result of the decreased resistance in series with the field winding GF, a greater current flows through the field winding and increases the excitation of the field of the generator G so that the 60 latter generates a greater voltage and thus the motor M is accelerated to cause the elevator car to travel at a predetermined intermediate speed.

Just prior to the time that the elevator motor 65 M attains the intermediate speed, the voltage-responsive relay 31 is energized to close its contact members and thereby complete a circuit for energizing the coil of relay GR6, which circuit extends from supply conductor L1 through conductor 21, section 12 of the car switch, contact finger 17, conductor 52, normally open contact members h of relay 1, conductor 53, contact members 3UL of inductor relay 3R, conductors 54 and 55, contact members of relay 31, conductor 56, coil of 75

relay GR6 and conductor 57 to supply conductor L2.

The closing of normally open contact members *d* of relay GR6, upon the energization thereof, completes a self-holding circuit which is connected in parallel-circuit relation with sector 12 and contact finger 17 of the car switch CS between supply conductor L1 and contact members *h* of relay 1, so that the relay GR6 is maintained energized independently of the engagement of sector 12 and contact finger 17.

The closing of normally open contact members *b* of relay GR6 completes a circuit for energizing the relay 3 which circuit extends from supply conductor L1 through conductor 58, coil of relay 3, conductor 59, contact members *b* of relay GR6 and conductor 60 to supply conductor L2.

The closing of normally open contact members *d*, as a result of the energization of relay 3, completes a self-holding circuit for maintaining the relay energized independently of contact members *b* of relay GR6, which holding circuit extends from supply conductor L1 through conductor 58 and the coil of relay 3 thence through conductors 59 and 61, contact members *d* of relay 3, conductors 62 and 63, contact members *b* of relay 3OD, which were closed as previously described, and conductors 64 and 65 to supply conductor L2.

The opening of normally closed contact members *a* of relay 3 removes the short-circuiting connection around resistor R3 and thus reinserts the resistor R3 in series-circuit relation with the generator shunt field winding GF. Similarly, the opening of normally closed contact members *b* and the closing of normally open contact members *c* of relay 3 reduces the amount of the potentiometer resistor PR included in series-circuit relation with the generator field winding GF. The effect of reinserting the resistor R3 and/or decreasing the amount of the potentiometer resistor PR effective to compound the excitation of the field winding GF would be to effect a reduction in the speed of the elevator car, except for the fact that the resistor R2 is simultaneously short-circuited by the closing of the normally open contact members *a* of relay GR6.

The normally open contact members *a* of relay GR6, when closed as a result of the energization of the relay, complete a short-circuit connection around the resistor R2 and thus cause the current through the generator field winding GF to be still further increased, which ultimately results in the elevator motor M being accelerated to drive the elevator car 1 at its maximum or high speed.

As long as the elevator operator desires to cause the elevator car to continue to travel at high speed, he holds the handle of the car switch in its extreme displaced position in a clockwise direction. As he approaches the floor at which he desires to stop the elevator car, in this case assumed to be the upper terminal floor, the operator centers the car-switch, that is, returns the handle of the car-switch to its central position.

The sector 12 of the car-switch reengages the contact finger 14 when the car-switch handle is returned to its central position, and a circuit is thereby completed for energizing the coil 3L of inductor relay 3R, which circuit extends from supply conductor L1 through conductor 21, sector 12 of the car-switch, contact finger 14, conductors 66 and 67, normally open contact members *f* of relay 1, conductor 68, coil 3L of inductor relay 3R and conductor 69 to supply conductor L2.

The elevator car continues to travel at high speed until the inductor relay 3R on the car

comes into closely adjacent relation to the high-speed up-direction inductor plate 3U for the upper terminal floor, that is the floor at which it is desired the car should stop. The contact members 3UL of inductor relay 3R are thereby actuated to an open position and interrupt the circuit, previously traced, for energizing the coil of relay GR6. As a result, relay GR6 is deenergized and the contact members *a* thereof are opened to remove the short-circuit connection around resistor R2 and to effect its reinsertion in the circuit of the generator field winding GF. A reduction in the current through the generator field winding GF is thus effected and the motor is decelerated to cause the car to travel at the intermediate speed. The opening of contact members *b* of relay GR6 is without effect, since the relay 3 is maintained energized through the holding circuit previously traced.

The opening of contact members *d* of relay GR6 is likewise without effect, since the self-holding circuit for relay GR6 which is maintained thereby, has been otherwise interrupted by the opening of contact members 3UL of inductor relay 3R.

The reclosing of normally closed contact members *c* of relay GR6, however, completes a circuit for energizing the coil 2L of inductor relay 2R, which circuit extends from supply conductor L1 through conductor 21, sector 12 on the car switch CS, contact finger 14, conductors 66 and 67, contact members *f* of relay 1, conductors 68 and 70, coil 2L of inductor relay 2R, conductor 71, contact members *c* of relay GR6 and conductor 72 to supply conductor L2.

As the elevator car continues to travel at the intermediate speed, relay 2R comes into closely adjacent relation to the intermediate-speed up-direction inductor plate 2U, corresponding to the upper terminal floor, and the contact members 2UL thereof are thus actuated to an open position to interrupt the circuit, previously traced, for energizing the relay GR4.

The opening of contact members *a*, as a result of the deenergization of relay GR4, removes the short-circuiting connection around resistor R1 and this results in a further decrease of the current through the generator field winding GF and ultimately in the deceleration of the elevator car to low speed.

The opening of contact members *c* of relay GR4 is without effect, since the holding circuit maintained thereby for energizing relay GR4 has been previously opened by the opening of contact members 2UL.

The reclosing of normally closed contact members *b* of relay GR4 completes a circuit for energizing the coil 1L of inductor relay 1R, which circuit extends from supply conductor L1 through conductor 21, sector 12 on the car-switch, contact finger 14, conductors 66 and 67, contact members *f* of relay 1, conductors 68 and 73, coil 1L of inductor relay 1R, conductor 74, contact members *b* of relay GR4 and conductor 75 to supply conductor L2.

The elevator car continues to travel at low speed until the relay 1R comes into closely adjacent relation to the up-direction stopping inductor plate 1U for the upper terminal floor, at which time contact members 1UL of inductor relay 1R are caused to be opened and interrupt the circuit, previously traced, for energizing the up-direction relay 1. As a result of the deenergization of relay 1, the circuits, previously traced, for severally energizing the generator shunt field winding GF

and the release coil R_5 of the brake B , are interrupted with the results that the elevator car stops and the brake B is applied to the motor M to maintain the elevator car in position at the 5 terminal floor in exact alignment therewith.

The opening of normally open contact members f of relay 1, as a result of the deenergization of relay 1, interrupts the several circuits, previously traced, for energizing the coils 1L, 2L and 3L of 0 the inductor relays and thus the coils become deenergized.

Now let it be assumed that the operator desires to make a so-called one floor run, that is, descend to the floor immediately below the terminal floor.

5 To effect such movement of the elevator car, the operator may move the car-switch handle in a counter clockwise direction, hold it momentarily in its extreme displaced position and then return it to its central position. The engagement of 0 sector 12 on the car-switch with the stationary contact finger 18 completes a circuit for energizing down-directional relay 2, which circuit extends from supply conductor L1 through conductor 21, sector 12, contact finger 18, conductor 5 76, coil of relay 2, conductor 77, contact members 1DL of inductor relay 1R, conductors 78 and 24, and thence through gate-switch g , door-interlock switches d and safety switches ss , in series, to supply conductor L2.

0 The normally closed contact members d of relay 2, when opened as a result of the energization of the relay, interrupt the circuit for energizing relay 80 D, previously traced, and the self-holding circuit for maintaining relay 3 energized is thus interrupted by the opening of contact members b of relay 80 D. The reclosing of contact members a of relay 80 D completes a circuit for energizing relay 80 U, as previously traced, but due to the fact that the contact members d 0 of relay 3, have already opened, the closing of contact members b of relay 80 U is ineffective to complete a circuit for energizing relay 3. Relay 3, therefore, becomes and remains deenergized. Contact members a of relay 3, when closed as 5 a result of the deenergization of the relay, complete a short-circuiting connection around the resistor R_3 and the contact members b of relay 3 reclose to connect the armature winding of generator RG in series-circuit relation with the generator field winding GF .

When contact members b and c of relay 2 close as a result of the energization of the relay, they complete a circuit for energizing the generator field winding GF in a reverse direction to that 5 effected by the closing of contact members b and c of relay 1 so that the voltage generated by the generator G is of reverse polarity and the motor M is thus caused to rotate in such a direction as to move the elevator car downwardly.

10 The circuit for energizing the generator field winding GF , as established by the closing of contact members b and c of relay 2, extends from supply conductor L1 through conductor 79, contact members c of relay 2, conductors 80 and 40, 15 armature winding of generator RG , contact members b of relay 3, conductor 39, field winding GF , conductors 38, 81 and 82, contact members b of relay 2 and conductors 83 and 41 to the point 42, thence through conductor 43, contact members a of relay 3 and conductors 44 and 45 to the point 46, thence through resistors R_2 and R_1 to supply conductor L2.

Contact members a of relay 2 are connected in parallel-circuit relation with contact members a 5 of relay 1 and thus, when contact members a

of relay 2 are closed as a result of the energization of the relay, the release coil R_5 of the brake B on the motor M , is energized through a circuit substantially identical with that previously traced therefor.

The elevator car is thus initially caused to travel at low speed in a down direction. It is to be noted that my invention embodies the feature, just described, whereby the resistor R_3 is short circuited and/or the connections to the 10 potentiometer resistor PR are changed. The effect of short-circuiting the resistor R_3 and/or changing the connections to the potentiometer resistor PR is to overexcite the generator field winding to a predetermined amount necessary to 15 overcome the opposing magneto-motive force exerted by the residual magnetism in the field coils of the generator G , which residual magnetism exerts a magneto-motive force in opposition to the magneto-motive force created by the current flowing through the generator field winding GF . As a result, therefore, the generator G generates 20 a normal voltage, that is, such a voltage as will cause the elevator motor M to drive the elevator car at a predetermined low speed.

5

Although the car-switch handle is centered, the energization of relay 2 is maintained by normally open contact fingers e of relay 2 which complete a self-holding circuit in parallel-circuit relation with the car-switch sector 12 and contact finger 18 between supply conductor L1 and the coil of relay 2.

25

As a result of the engagement of sector 12 on the car switch with the contact finger 19, a circuit is completed for energizing relay GR_4 , which extends from supply conductor L1 through conductor 21, sector 12, contact finger 19, conductor 85, contact members g of relay 2, conductor 86, contact members 2DL of inductor relay 2R, conductor 50, coil of relay GR_4 and conductor 51 to supply conductor L2.

30

Contact members a of relay GR_4 , when closed complete a short-circuiting connection around resistor R_1 which results in an increase in current through the generator field winding GF and ultimately in the acceleration of the motor M to drive the elevator car at the intermediate speed. Normally open contact members c of relay GR_4 45 complete a self-holding circuit for the relay as previously described, since they are connected in parallel-circuit relation with the sector 12 and contact finger 19 of the car switch CS. The elevator car is thus maintained at intermediate speed regardless of the centering of the car switch handle.

50

Due to the fact that the car switch handle was centered by the operator almost immediately after its displacement from the central position, relay GR_6 cannot become energized because the high-speed circuit for energizing the coil of relay GR_6 is not completed by the mere engagement of sector 12 and contact finger 20 of the car switch. Although the sector 12 and contact finger 20 are momentarily in engagement, if the contact members of the voltage responsive relay 60 65 31 have not been previously actuated to a closed position, due to the fact that the motor M has not accelerated sufficiently, the relay GR_6 cannot become energized.

The elevator car cannot, therefore, travel at a speed greater than the intermediate speed, and it continues to travel at the intermediate speed until the inductor relay 2R on the elevator car comes into closely adjacent relation to the down-direction intermediate-speed inductor plate 2D.

70

75

At such time, the contact members 2DL of relay 2R are actuated to an open position and thereby interrupt the circuit, previously traced, for energizing relay GR4. Relay GR4 is thus deenergized and the contact member *a* thereof opened to remove the short-circuiting connection around resistor R1. The re-insertion of resistor R1 in the circuit of the generator field winding reduces the amount of current flowing therethrough 10 and ultimately results in the deceleration of the elevator motor to drive the elevator car at low speed.

The elevator car continues to travel at low speed until the inductor relay 1R on the elevator 15 car comes into closely adjacent relation with the down-direction stopping inductor plate 1D for the ninth floor. Contact members 1DL of relay 1R are thereby actuated to an open position to interrupt the circuit, previously traced, for energizing relay 2. The opening of contact members *a*, *b* and *c* of relay 2 interrupt the circuits previously traced for energizing the release coil R_s and the generator field winding GF. As a result, 20 the elevator motor stops the elevator car in exact alignment with the ninth floor and the brake B is applied to maintain the car in position thereat.

The opening of normally open contact members *f* of relay 2, as a result of the deenergization of 25 relay 2, interrupts the circuit for energizing the coils 1L, 2L, 3L of the inductor relays 1R, 2R and 3R, respectively. It will thus be seen that the inductor relays are energized only during the landing period and at all other times no power is required for their energization.

30 Now let it be supposed that the operator desires the car to travel downwardly to the lower terminal floor, he may move the handle of the car-switch in a counter-clockwise direction into its extreme displaced position, holding it there until 40 such time slightly before the elevator car arrives at the landing zone defined by the inductor plates 3D, 2D and 1D for the lower terminal landing at which time he may center the car-switch.

The operation of the control system is the same 45 as just previously described for the movement of the car from the top terminal floor to the next lower floor up until the time that the elevator car attains the intermediate speed. Due, however, to the fact that the car-switch handle is maintained in its displaced position, sector 12 remains in engagement with the contact finger 20 and thus, upon the closing of the contact members of the voltage-responsive relay 31, a circuit is completed for energizing the relay GR6, which 50 circuit extends from supply conductor L1 through conductor 21, sector 12, contact finger 20, conductor 88, contact members *h* of relay 2, conductor 89, contact members 3DL of inductor relay 3R, conductor 55, contact members of relay 31, 55 conductor 56, coil of relay GR6 and conductor 57 to supply conductor L2.

Contact member *a* of relay GR6 complete a short circuiting connection around resistor R2 to accelerate the elevator car to high speed in the 60 manner similar to that described for the up-direction of travel of the car. Contact members *d* of relay GR6, when closed by the energization of the relay, complete a self-holding circuit for maintaining the relay energized due to the fact 65 that they are connected in parallel-circuit relation with the contact segment 12 and the contact finger 20 of the car switch.

When contact members *b* of relay GR6 close, due to the energization thereof, relay 3 is again 70 energized through the circuit, as previously traced,

and contact members *a*, *b* and *c* of relay 3 function as before to remove the short-circuiting connection from resistor R3 and reduce the amount of the potentiometer resistance PR in series-circuit relation with the generator field winding GF.

The closing of contact members *d* of relay 3 completes a self-holding circuit for maintaining the relay energized, which circuit extends from supply conductor L1 through conductor 58, coil 10 of relay 3, conductors 59 and 61, contact members *d* of relay 3, conductor 62, contact members *b* of relay 80 U and conductor 65 to supply conductor L2.

It will thus be noted that in the case of the 15 elevator car attaining only intermediate speed, the resistor R3 becomes short-circuited and the connections to the potentiometer resistor PR are so changed that the armature winding of generator RG is connected in series-circuit relation 20 with the generator field winding GF whereas when the elevator car accelerates to high speed, the resistor R3 is not short-circuited and only a portion of potentiometer resistor PR is connected in series circuit relation with the generator field winding 25 GF instead of the armature winding.

I have found that in the case of the elevator car accelerating to the highest speed, the degree of excitation of the generator field winding GF is sufficient to reverse the residual magnetism in 30 the field cores of the generator G so that its effect thereafter is not subtractive in its effect on the generator voltage until such times as the excitation of the generator shunt field winding is again reversed.

The car continues to travel at high speed until such time as the operator centers the car switch whereupon the inductor relay coil 3L is energized and the sequence of operations for effecting the deceleration and stopping of the elevator car at 40 the lower terminal floor is effected by the successive opening of the contact members 3DL, 2DL and 1DL of the inductor relays 3R, 2R and 1R respectively, in the manner substantially similar to that already described for the stopping of the car 45 at the upper terminal landing.

The employment of relay 3 for the purpose of controlling resistor R3 and the potentiometer resistor PR and thereby over-exciting the generator field winding GF to a predetermined amount necessary to overcome the opposing effect of the residual magnetism in the field cores of the generator G when the initial run of the elevator car immediately after reversal, is such that it attains only an intermediate speed, effects the consistent operation of the elevator car at an intermediate speed which enables the elevator car to conform closely to a predetermined speed characteristic for that type of run. If relay 3 were not employed, the speed of the elevator car would be decreased due to the effect of the residual magnetism, over that required to cause the elevator car to travel in conformity with a predetermined speed characteristic for a short run such as that between two adjacent floors.

It should be understood that, while I have disclosed a control system adapted to cause the elevator car to travel at only three speeds, namely, low speed, intermediate speed and high speed, it may readily be adapted to cause the car to travel at a greater number of different speeds. It should, furthermore, be understood that additional relays corresponding to relay 3 may be employed for the purpose of functioning in a similar manner as between an intermediate speed and another 7

lower intermediate speed so that the excitation of the generator field winding may be further controlled for the purpose of varying the extent of over-excitation of the generator shunt field winding, depending upon whether the elevator car accelerates to one intermediate speed or another intermediate speed.

In conclusion, therefore, it will be seen that I have disclosed a control system embodying means for compensating for the effect of residual magnetism in dynamo-electric devices employed in the system, whereby consistent conformity of a motor speed curve with a predetermined speed curve is obtained regardless of whether the motor accelerates to an intermediate speed or maximum speed immediately after a reversal in its direction of movement. Obviously, my invention is not limited in scope, merely to elevator applications, although it is especially useful in connection therewith.

It should be understood that my invention is capable of various modifications and adaptations without departing from the spirit thereof and that I do not desire to limit the scope thereof except as necessitated by the prior art and as defined by the appended claim.

I claim as my invention:

In a control system for a motor, a generator including a field winding for supplying power to said motor, a reversible circuit associated with said winding, resistance in said circuit, a controller for said motor including means for reversing said field winding circuit and high speed contacts, a switch for controlling a section of said resistance, an actuating circuit for said switch including said high speed contacts, a self-holding circuit for said switch, and means, responsive to operation of said controller to reverse said field winding circuit, for interrupting said self-holding circuit.

DANILO SANTINI. 20
